UNITED STATES PATENT OFFICE.

GEORGE ERTEL, OF FORT WAYNE, INDIANA.

CISTERN-COVER.

No. 843,801.

Specification of Letters Patent.

Patented Feb. 12, 1907.

Application filed May 19, 1906. Serial No. 317,841.

To all whom it may concern:

Be it known that I, GEORGE ERTEL, a citizen of the United States, residing at Fort Wayne, in the county of Allen, in the State of Indiana, have invented certain new and useful Improvements in Cistern-Covers; and I do hereby declare that the following is a full, clear, and exact description of the invention, which will enable others skilled in the art to 10 which it appertains to make and use the same, reference being had to the accompanying drawings, which form part of this specification.

My invention relates to improvements in 15 cistern-covers.

The objects of my present invention are to provide a cistern-cover having a tapering cast-metal neck instead of the usual brick-wall neck, thereby obviating the disintegrating effect of freezing of the mortar between the bricks and avoiding the necessity of the usual annular metal plate which rests upon the brick wall, and to which the cover is secured, and to provide a novel cap adapted for 25 an interlocking engagement with the cast-metal neck and having a novel form of adjustable slide adapted to snugly fit either a five or a six inch pump-stock and also having the angular central opening so constructed as to 30 permit a proper turning of the pump to fit the opening when it is placed in position and also having a ventilating opening in the means for securing the adjustable slide in position.

35 My invention consists of a cistern-cover having a tapering open-ended metal neck, a circular cap adapted for an interlocking union with the upper end of the neck, and having a radial opening to permit the lateral 40 adjustment of the pump-stock into position, an adjustable slide for the said opening and means for rigidly securing the slide in position.

Similar reference-numerals indicate like 45 parts throughout the several views, in which—

Figure 1 is a plan view of my improved cap, partly broken away to show the means for securing the slide in position and also 50 showing in dotted outline the forward adjustment of the slide to fit a five-inch pump. Fig. 2 is a vertical central section of my improved cap taken on the line $x-x$ of Fig. 1 with the adjustable slide removed. Fig. 3

is a vertical central section of my invention 55 on the line $y-y$ of Fig. 1, the metal neck being broken away in part. Fig. 4 is cross-section of the adjustable slide on the line $z-z$ of Fig. 1, partly broken away, showing the means for locking the slide in position and also showing 60 the ventilating means. Fig. 5 is a bottom plan of the plug which carries the interlocking means and showing the radial lugs by means of which the ventilating-openings are provided. Fig. 6 is a detail of the central 65 opening in the cap, showing the opposite obtuse angles by means of which the pump-stock can readily be turned in adjusting it to position therein.

The cast-metal neck 1, circular in cross-section and slightly tapering, as shown, is open at both top and bottom, has an outer peripheral flange 2 upon its lower end adapted to rest upon the top of the cistern, and is rigidly secured thereon by mortar in the usual 70 manner, and has an inner annular flange 3 upon its upper end to aid in supporting and securing the removable cap about to be described. This flange 3 has two diametrically 75 opposite vertical slots 8 for the purpose here- 80 inafter described.

The cap 4 is circular in contour, has a down-turned perimeter 5, whose edge rests firmly upon the top of the neck 1, and is provided with a pair of oppositely-arranged pendent 85 lugs 6, having an outwardly-projecting point or hook 7, adapted for an interlocking engagement with the lower face of the flange 3, as shown in Fig. 3. The cap 4 has a radial opening 9, whose inner end terminates in the 90 right-angular sides 10, one of which has a vertical slot 11 for the usual slide to let the water of the pump-stock out to prevent freezing in a well understood manner. The parallel 95 sides of this opening 9 have an upright longitudinal flange 12 and a pendent longitudinal flange 13, Fig. 4.

A longitudinally-adjustable slide 14, having raised lateral longitudinal flanges 15, 100 adapted to slidably rest upon the flanges 12, is adapted to close the opening 9 when the pump is in position. This slide 14 has its forward or inner end provided with the right-angular sides 16, which in conjunction with the respective opposite sides 10 of the opening 9 form a rectangular opening 17 for the pump-stock, Fig. 1, which, as shown, is 105 adapted to snugly fit a six-inch pump-stock,

- and when the slide 14 is forwardly adjusted, as shown by the dotted outline, this contracted opening is adapted to snugly fit a five-inch pump-stock. The opening 17 of 5 the cap has two flaring sides 18, forming obtuse angles with the respective sides 10, Fig. 6, whereby when it is desired to either remove or replace the cap 4 it can readily be done laterally, since the said obtuse angles 10 permit the pump-stock to be so turned in the opening 17 as to readily pass through the opening 9. The slide 14 has a central opening surrounded by an upright flange 19. In 15 this opening is loosely and rotatably mounted a plug 20, having an overhanging flange 21, provided upon its lower face with a plurality of pendent lugs 22, adapted to rest upon the flange 19, thereby leaving an air-space between the same. On the lower angular end of this plug is mounted a latch 23, secured in position by means of a pin 24 and adapted to normally engage the lower face of the flanges 13 to firmly secure the said slide in position.
- 25 The operation and manner of employing my invention thus described is obvious and, briefly stated, is as follows: When the metallic neck 1 is employed instead of the usual cistern-neck of brick, it is apparent that it cannot be disintegrated or otherwise affected by freezing and also that it can be more conveniently and economically employed and also that when it is employed the use of the usual annular plate is avoided. The cap 4 is readily placed in position by first passing the opposite lugs 6 through the opposite slots 8 in the flange 3, after which the cap is given a sufficient turn to securely interlock the hooks 7 of lugs 6 with the flange 3. The pump- 30 stock is next placed in position by passing it down through the opening 9 and then adjusting it in position in the opening 17, after which the slide 14 is placed upon the flanges 12 and then so adjusted that the sides 16 35 snugly abut the adjacent sides of the pump-stock, after which the plug 20 is rotated until 40 the latch 23 is arranged transversely of the opening 9 and in a holding engagement with the flanges 13.
- Having thus described my invention and 50 the manner of employing the same, what I desire to secure by Letters Patent is—
1. In a cistern-cover, a beveled tapering metal neck having a vertically-slotted flange on its upper end; a cap having upon its lower face pendent lugs adapted to engage the said flange, and provided with a radial opening whose inner end terminates in right-angular sides; an adjustable slide or cover for the said opening whose inner end has angular sides to 55 coöperate with the said angular sides to form a rectangular vertical central opening, and provided with means for rigidly securing the said slide in position.
  2. In a cistern-cover, the combination of 60 an open-ended metal neck; a circular cap having a radial opening and means for interlocking the same with the said neck; and an adjustable slide or cover for the said opening adapted to form a central angular opening, and provided with means for rigidly securing the 65 same in position.
  3. In a cistern-cover a circular cap having a radial slot or opening, and provided with means for securing the same in position; an 70 adjustable slide or cover for the said opening; and means for rigidly securing the said slide in position.
  4. In a cistern-cover a circular cap having a radial slot whose inner end terminates in 75 angular sides, and opposite obtuse angles; an adjustable slide or cover for the said slot whose inner end is provided with angular sides for the purpose described; and means for rigidly securing the said slide in position. 80
- Signed by me at Fort Wayne, Allen county, State of Indiana, this 17th day of May, A. D. 1906.
- GEORGE ERTEL.
